US00D873995S

(12) **United States Design Patent** (10) **Patent No.:** **US D873,995 S**
(45) **Date of Patent:** **** Jan. 28, 2020**

(54) **UROFLOWMETER**

- (71) Applicant: **ClearTrac Technologies, LLC**,
Elizabethton, TN (US)
- (72) Inventors: **Brent Laing**, Greenwood Village, CO
(US); **John Green**, Elizabethton, TN
(US); **Paul R. Johnson**, Boulder, CO
(US); **Robert John Smith**, Louisville,
CO (US); **Robert Edwin Schneider**,
Erie, CO (US); **Magnus Hargis**,
Hudson, CO (US); **Elise Geolat Edson**,
Boulder, CO (US); **Elizabeth A.
O'Brien**, Louisville, CO (US)
- (73) Assignee: **CLEARTRAC TECHNOLOGIES,
LLC**, Elizabethton, TN (US)
- (**) Term: **15 Years**
- (21) Appl. No.: **29/649,761**
- (22) Filed: **Jun. 1, 2018**
- (51) LOC (12) Cl. **24-02**
- (52) U.S. Cl.
USPC **D24/122**
- (58) Field of Classification Search
USPC D10/96, 102; D24/121, 122, 123, 133
CPC A61B 10/007; B01L 3/00; B01L 2300/08

(57) **CLAIM**

The ornamental design for a uroflowmeter, as shown and described.

DESCRIPTION

FIG. 1 shows a front perspective view of a uroflowmeter; FIG. 2 shows a right elevation view of the uroflowmeter of FIG. 1; FIG. 3 shows a left elevation view of the uroflowmeter of FIG. 1; FIG. 4 shows a front elevation view of the uroflowmeter of FIG. 1; FIG. 5 shows a rear elevation view of the uroflowmeter of FIG. 1; FIG. 6 shows a top view of the piece of the uroflowmeter of FIG. 1; and, FIG. 7 shows a bottom view of the uroflowmeter of FIG. 1. The broken lines in FIGS. 1-7 illustrate portions of the uroflowmeter and form no part of the claimed design.

1 Claim, 5 Drawing Sheets
